(57) **CLAIM**

The ornamental design for the disposable shopping cart cover or highchair cover, as shown and described.

DESCRIPTION

FIG. 1 is a top elevational view of a disposable shopping cart cover or highchair cover showing my new design;

FIG. 2 is a bottom elevational view thereof;

FIG. 3 is a right elevational view thereof;

FIG. 4 is a left elevational view thereof;

FIG. 5 is a front elevational view thereof;

FIG. 6 is a bottom elevational view thereof;

FIG. 7 is an isometric elevational view thereof; and,

FIG. 8 is an in-use view of the device on a highchair.

The break lines shown in FIGS. 1-4 and 7 symbolize breaks in the length of the article in which the claimed design is embodied. The appearance of any portion of the article between the break lines form no part of the claimed design.
